JET ENGINE COMBUSTION SYSTEM HAVING
BURNER IN THE JET PIPE AND CONTROL-
LING MEANS THEREFOROwen Napier Lawrence, Dorrige, England, as-
signor to Joseph Lucas Limited, Birmingham,
England

Application October 27, 1950, Serial No. 192,411

Claims priority, application Great Britain
November 17, 1949

3 Claims. (Cl. 60—35.6)

1

This invention relates to the combustion systems of jet engines, of the kind in which the system (or each of an associated group of such systems) comprises an elongated combustion chamber which at one end is provided with a liquid fuel burner and is adapted for the admission thereto of air from a blower, the other end terminating in an extension which forms the jet pipe, and in which there is mounted, between the adjacent ends of the combustion chamber and jet pipe, the rotor of a turbine which actuates the blower.

In some such systems provision is made for admitting additional liquid fuel to a burner in the jet pipe, when it is required to augment the energy of the gases therein after passing the turbine and before discharge to the atmosphere. It is undesirable however, to admit the additional fuel at an excessive rate. The permissible maximum rate of supply is not a fixed quantity, but is dependent on contemporary working conditions in the system, and the object of the present invention is to enable the rate of supply to be automatically controlled in a satisfactory manner.

The invention comprises the combination with the system, of means for controlling the additional fuel under the joint action of the pressure of the air at the blower inlet, and the pressure of the gas in the jet pipe between the turbine and the point of admission of the additional fuel.

The invention also comprises means as specified in the preceding paragraph, in which the relative effects of the said pressures is variable under manual control.

In the accompanying drawing, Figures 1 and 2 are diagrams illustrating two embodiments of the invention.

Referring to Figure 1, the principal combustion chamber of a jet-engine is represented by *a*. In this is mounted a liquid fuel burner *b* which is supplied by a pump at a variable rate in response to the control of the pilot and of conditions associated with the working of the engine, such as speed, or atmospheric pressure. The blower for air required in the combustion chamber is represented by *c* and this is driven by a turbine *d* situated at the discharge end of the combustion chamber. In the extension or jet-pipe *e* of the combustion chamber is arranged a burner *f* by which the additional fuel is supplied, and it is the control of this fuel which forms the subject of the present invention.

In the example illustrated at Figure 1, the extra fuel is supplied by a rotary pump *g* of the swash plate type, the output of the pump being

variable by adjustment of the obliquity of the swash plate *h* under the action of a fuel-operated servo-mechanism. This mechanism is of known form and comprises a cylindrical chamber *i* containing a piston *j* loaded by a spring *k* and connected to the swash plate by a rod *m*. One end of the cylinder *i* is in communication with the discharge passage *n* of the pump by way of a passage *o*, and the other end is in communication with the passage *n* by way of a restricted passage *p*. The end of the cylinder *i* containing the spring *k* communicates with the seating *q* of a control valve *r* by way of a passage *x*. The arrangement is such that when the valve *r* is closed, the liquid pressures acting on opposite sides of the piston *j* are balanced, and the spring *k* then moves the piston in the direction for increasing the pump output. When the valve *r* is opened, a preponderating liquid pressure acts on the side of the piston in opposition to the spring and moves the piston in the direction for reducing the pump output.

The valve *r* is mounted on a lever *s* which is carried by a flexible diaphragm *t*, or is pivotally mounted on a partition, which separates two compartments *u*, *v*, in a chambered body part, the compartment *u* being in communication with the pump inlet, or a sump. The end of the lever which extends into the compartment *v* is connected by a link *z* to a diaphragm *3*. One side of the diaphragm is subject to the pressure of the air at the inlet side of the blower *c*, a passage *4* being provided between the blower inlet and the compartment *v*. The other side of the diaphragm is subject to the pressure of the gases at the exit side of the turbine *d*, a passage *5* being provided for effecting communication between the said side of the turbine and diaphragm.

In the chamber *v* is also contained another lever *6* loaded by a spring *7* and evacuated capsule *8*. Between the two levers *s*, *6* is arranged a slidable abutment *9* by which force can be transmitted from one lever to the other, and the position of the abutment relatively to the lever is movable under the manual control of the pilot through a lever *10*. By appropriately adjusting the position of the abutment *9* the forces acting on the valve lever *r* can be varied as desired.

Assuming that the pressures acting on the diaphragm *3* and capsule *8* are such that the valve *r* is slightly open, and that the piston *j* is in equilibrium at a position intermediate the ends of the chamber *i*, it will be seen that the pressure exerted on the left hand side of the piston by liquid admitted to the corresponding end of the

chamber through the passage *o* is balanced by the pressure exerted on the other side of the piston by the combined effect of the spring *k* and the liquid admitted to the right hand end of the chamber through the restricted passage *p*, the liquid pressure in the last mentioned end of the chamber being partially relieved by leakage of liquid past the valve *r*. If now the valve *r* is opened to a greater extent by relative variation of the pressures acting on the diaphragm *3* and capsule *8*, the liquid pressure in the right hand end of the chamber *i* will be further relieved, and the piston will be moved against the action of the spring *k* by the preponderating liquid pressure in the left hand end of the chamber to cause reduction of the pump output until a new condition of equilibrium is reached. Closing movement of the valve *r* by relative variation of the pressures acting on the diaphragm *3* and capsule *8* has a reverse effect to that above described, and enables the spring *k* to move the piston *j* for increasing the pump output. Movement of the abutment *9* under the control of the pilot varies the effect of the capsule *8* on the lever *s* without varying the effect of the diaphragm *3* on this lever.

It will be apparent therefore, that by the arrangement above described, the rate of supply of fuel from the pump *g* to the burner *f* is automatically controllable by the pressures acting on the diaphragm *3*, the air pressure acting on the capsule *8* and the load exerted by the spring *7*, the effect on the valve *r* being variable under the control of the pilot through the lever *10* and abutment *9*.

The embodiment shown in Figure 2 differs from that shown in Figure 1, in that the one pump *g* supplies liquid fuel to both of the burners *b*, *f*. In this example the servo-mechanism *i*, *j*, *k*, *o*, *p* above described serves mainly to control the supply of fuel to the burner *b*, and this is effected in response to any control device positioned as indicated by *13* in the diagram between the servo-mechanism and the burner *b*. The supply of fuel from the pump to the burner *f* is mainly controlled by a throttle *11*, which is actuated by a second servo-mechanism indicated generically by *12* and which is essentially similar to the one above described with reference to Figure 1. The servo-mechanism *12* is controlled by a similar valve mechanism to that already described, similar reference characters being used in Figure 2 to identify the valve mechanism.

Having thus described my invention what I

claim as new and desire to secure by Letters Patent is:

1. A jet-engine combustion system having in combination an elongated combustion chamber, a main burner in the combustion chamber, a blower for supplying air under pressure to one end of the combustion chamber, a turbine at the other end of the combustion chamber, a jet pipe extending from the last mentioned end of the combustion chamber, an auxiliary burner in the jet pipe, means for supplying liquid fuel to the auxiliary burner, a liquid-operated servo-mechanism for determining the quantity of liquid fuel supplied to the auxiliary burner, control means responsive to the air pressure at the blower inlet, additional control means responsive to the gas pressure in the jet pipe between the turbine and the auxiliary burner, and a control member responsive to the combined action of the two control means for controlling the action of said servo-mechanism.
2. A jet-engine combustion system as claimed in claim 1 and having manually adjustable means for varying the combined effect of said two control means on said control member, said manually adjustable means being formed in part by a motion-transmitting abutment through which one of said two control means acts on said control member.
3. A jet-engine combustion system as claimed in claim 1, in which the means for supplying liquid fuel to said auxiliary burner comprises a pump which serves also for supplying fuel to said main burner, and in which a throttle operable by the liquid-operated servo-mechanism is provided for controlling the quantity of liquid fuel supplied to said auxiliary burner.
